UNITED STATES PATENT OFFICE.

LEWIS F. WEBER, OF FRANKFORT-ON-THE-MAIN, GERMANY, ASSIGNOR TO UNITED SHOE MACHINERY COMPANY, OF PATERSON, NEW JERSEY, A CORPORATION OF NEW JERSEY.

EYELETING-MACHINE.

1,119,911.

Specification of Letters Patent.

Patented Dec. 8, 1914.

Application filed August 28, 1909. Serial No. 515,049.

To all whom it may concern:

Be it known that I, LEWIS F. WEBER, a citizen of the United States of America, residing at Frankfort-on-the-Main, Germany, have invented certain Improvements in Eyeleting Machines, of which the following description, in connection with the accompanying drawings, is a specification, like reference characters on the drawings indicating like parts in the several figures.

This invention relates to machines for setting fasteners, such as eyelets, lacing hooks and the like, in the uppers of boots and shoes, and relates particularly to devices whereby the work may be held firmly during the setting operation of the machine.

Heretofore in eyeleting closed uppers it has been difficult to hold the work during the setting of the lowest eyelet in each quarter for the reason that the juncture of the vamp, tongue and quarters forms a bunch or thick part in the location where the presser foot should engage the work. This thick part constitutes an obstruction which it is difficult to pass under a presser foot of the usual construction and so interferes with the setting of an eyelet in the required close proximity to the vamp. Even if the thick part is fed under the presser foot it affords an uneven and restricted bearing for the latter with the result that the work is liable to become displaced or twisted in the machine and injured by the punch or sets.

With these conditions in view it is an object of the present invention to provide a work holding device which shall engage the work over a considerable area, thus preventing displacement thereof, the location and arrangement of said device being such as to avoid the thick portion in the closed upper and permit feeding the upper to the sets without obstruction.

In feeding a right quarter to the sets the thick portion of the upper, mentioned above, falls at the left of the setting position, while in dealing with a left quarter the thick portion is upon the right side of this point.

An important feature of my invention consists in the provision of a work holding mechanism in which the right quarter is held and guided by a member located upon the right side of the setting position and the left quarter by a member located upon the left side.

A preferred embodiment of my invention comprises a presser foot consisting of two pivotally mounted parts either of which may be moved to operative or inoperative positions and locked in either of said positions. The operative position of one part is on the right side of the setting position whereby it is afforded an extensive bearing on the uneyeleted portion of the right upper and the thick portion of the upper lies beyond this part and moves away from it during the setting operation. On the other hand the operative position of the second part of the presser foot is on the left side of the setting position whereby the left quarter is eyeleted with equal convenience.

As herein shown the two parts of the presser foot are so mounted that one may be moved without effecting the position of the other. To this end the parts are journaled one above another to turn about a vertical axis, the shank of the longer part being offset from its work engaging end so as to clear the shank of the shorter part. An advantage of this construction is that both parts may be moved into inoperative positions in the same vertical plane and therefore occupy, in inoperative position, a location more remote from setting position and more out of the way of the work than would be the case if the two parts were connected. Moreover the independent mounting of each part tends to improve its bearing upon the work when in operative position.

These and other features of my invention will be best understood and appreciated from the following description of one embodiment thereof, selected for purposes of illustration and shown in the accompanying drawings, in which,

Figure 1 is a front elevation of the work holding mechanism showing the upper set and work table, and Fig. 2 is a plan view of the same.

The work table 12 is slotted at 14 to receive an anvil block upon which the punch 10 cuts and to permit the passage of the lower set for setting the eyelets in the work. As shown herein the punch 10 is provided with a clenching or upsetting shoulder and cooperates with the lower setting die in 105 clenching the barrel of a fastener upon the work. At the rear of the work table and mounted for vertical reciprocation upon any

convenient part of the machine is the rod 2 carrying upon its upper end the journal member 3. The presser foot consists of two parts 4 and 5 which are mounted to turn 5 upon the journal member 3. Each part of the presser foot has a portion adapted for use with one quarter of a closed upper and is provided with a rearwardly extending portion 8 provided with a spring pressed 10 plunger 6 coöperating with notches in the journal member 3 to hold the parts of the presser foot in one of two predetermined positions. For example, the part 4 is shown in its operative position by the full lines in 15 Fig. 2 in which position it holds and guides a left quarter, permitting the closed upper to be moved as far to the left as may be necessary for setting the lowest eyelet near the vamp. The dotted lines in Fig. 2 show the 20 part 4 in its inoperative position where it is entirely clear of the work and which position it occupies while the other part 5 of the presser foot is operative.

It will be apparent from Fig. 1 that the 25 work engaging ends of the presser foot parts lie in the same horizontal plane while the shank of the longer part 4 is bent sharply upwardly so that it may swing over the shank of the shorter part 5 without interference.

For retracting the spring pressed plungers 6 the levers 7 are provided, each being pivoted upon the portion 8 of a presser foot part and having its end so located as to be 35 within convenient reach of the operator.

Preferably the two parts of the pressing members 4 and 5 which are intended to engage the work are conformed to the shape 40 of the slot in the work table, each part extending some distance along the side of the slot and across one end thereof so as to engage the work over a considerable area.

The rod 2 which carries the two parts of the presser foot has suitable connections 45 (not shown) with mechanism for intermittently lifting it to permit the work to be fed and also with a treadle whereby the presser foot may be raised for the insertion of the work, all of which mechanism is 50 well known in the art and requires no particular description in this place.

The operation of the work holding device will be clear from the foregoing description. In practice the two quarters are eyeleted 55 with their inside uppermost, the part 5 of the presser foot being operative during the eyeletting of the right quarter and being moved by the operator into its inoperative position when the left quarter is to be eyeleted and vice versa. In moving one of the presser foot parts to operative or inoperative position it is necessary only to press the appropriate finger lever 7 and then swing the presser foot part toward the 60 desired position. When this is reached the 65

spring locking pin enters the proper notch in the journal member and so automatically locks the part in position.

Having described my invention and illustrated a preferred embodiment thereof, what 70 I claim as new and desire to secure by Letters Patent is:—

1. A machine of the class described having, in combination, fastener setting devices, a work supporting table, and a presser foot 75 having two independently movable bearing members either of which may be moved into an inoperative position out of engagement with the work, one of the members being adapted for use with one quarter of an 80 upper and the other member with the opposite quarter.

2. A machine of the class described, having, in combination, fastener setting devices, a work supporting table, and a presser foot 85 having two pivotally mounted members arranged for use alternately, one of said members having a hook-shaped bearing portion open in one direction and the other having a hook-shaped bearing portion open in 90 the other direction, whereby they are adapted to engage the left and right quarters respectively of a shoe upper.

3. A machine of the class described, having, in combination, means for performing 95 a succession of operations on the work, a work supporting table, a vertical journal member, and a presser foot comprising two portions independently pivoted to turn horizontally about said journal member, each 100 portion having a radially extending shank one of which is located above the other and has a work engaging portion offset downwardly beyond the end of the other.

4. A machine of the class described, having, in combination, means for performing 105 a succession of operations on the work, a work supporting table, a vertical journal member, a presser foot comprising two portions pivotally mounted on said journal 110 member, and means for automatically locking either of said portions when it is moved into inoperative position.

5. A machine of the class described, having, in combination, means for performing 115 a succession of operations on the work, a work supporting table, a journal member, a presser foot comprising a plurality of members pivotally mounted on said journal member, and means for automatically locking 120 any one of said portions when it is moved into operative position.

6. A machine of the class described, having, in combination, means for performing 125 a succession of operations on the work, a work support and a presser foot having different portions constructed and arranged to engage the opposite quarters of an upper, locking means, for the presser foot and a pivoted lever extending within the reach 130

of the operator for releasing one of said portions preliminarily to moving the same into operative or inoperative positions.

7. A machine of the class described, having, in combination, means for performing a succession of operations on the work, a work support, a movable presser foot, locking means for said presser foot, and a pivoted lever having a handle extending without in the reach of the operator for actuating said locking means for unlocking said presser foot.

8. A machine of the class described, having, in combination, means for performing a succession of operations on the work, a work support, a presser foot comprising independently movable portions adapted to engage opposite quarters of an upper, spring locking means for each portion of the presser foot, and readily accessible, devices for operating said locking means for unlocking said movable portions.

9. An eyeleting machine, having a presser foot mounted for vertical reciprocation to clamp and unclamp the work, said presser foot comprising a separate horizontally movable portions shaped to engage opposite quarters of an upper over a considerable area and being so located as to avoid the thick portion formed by the juncture of the vamp and quarters of a closed upper, each portion having a radially extending shank one of which is located above the other and has a work engaging portion

offset downwardly beyond the end of the other.

10. A machine of the class described having, in combination, a work table having an elongated slot therein and a presser foot comprising independent work-engaging members, one of said members being shaped to bear upon the work at one end of said slot and the other member being shaped to bear upon the work at the other end of said slot.

11. A machine of the class described having, in combination, a work table, a coöperating presser foot comprising a journal member, a pair of radially extending arms arranged to swing in planes parallel to the work table and a work-engaging portion formed on the end of each of said arms and extending therefrom in relatively opposite directions.

12. A machine of the class described having, in combination, a work table having an elongated slot therein, and a presser foot comprising independently movable work-engaging members, together with devices for locking said work-engaging members in position adjacent to opposite ends of said slot.

In testimony whereof I have signed my name to this specification in the presence of two subscribing witnesses:

LEWIS F. WEBER.

Copies of this patent may be obtained for five cents each, by addressing the "Commissioner of Patents,
Washington, D. C."

It is hereby certified that in Letters Patent No. 1,119,911, granted December 8, 1914, upon the application of Lewis F. Weber, of Frankfort-on-the-Main, Germany, for an improvement in "Eyeleting-Machine," errors appear in the printed specification requiring correction as follows: Page 3, line 20, after the word "accessible" strike out the comma; same page, line 26, strike out the article "a"; and that the said Letters Patent should be read with these corrections therein that the same may conform to the record of the case in the Patent Office.

Signed and sealed this 23rd day of February, A. D., 1915.

[SEAL.]

J. T. NEWTON,

Acting Commissioner of Patents.
